UNITED STATES PATENT OFFICE.

CLARENCE N. HICKMAN, OF NEW YORK, N. Y.

MINE.

Application filed May 17, 1924. Serial No. 714,099.

To all whom it may concern:

Be it known that I, CLARENCE N. HICKMAN, a citizen of the United States, residing at New York, New York, have invented 5 new and useful Improvements in Mines, of which the following is a specification.

This invention relates to improvements in mines and more particularly to that class of submarine mines known as ballast or drifting mines.

As is well known to those familiar with the tactical use of inventions of this character, it is frequently desirable to discharge 15 from a pursued vessel, for example, a plurality of mines which float in its wake thereby to be engaged by the pursuing vessel to the damage or destruction of the latter.

These mines are not anchored in any way but drift freely for a predetermined time 20 and it is desirable, of course, that they occupy a position well below the surface of the water where their detection by the pursuing vessel will be difficult and also in a position to do the maximum damage to the vessel 25 below its water line.

It is, therefore, one of the objects of the present invention to provide a device of the above general character which will automatically calibrate the mine so that it will 30 assume a predetermined position below the surface of the water.

A further object is to provide a mechanism of the above general character which may be inexpensively manufactured and assembled and applied to mines now of standard equipment without material alterations 35 or modifications.

A further object is to provide a reliable and efficient mechanism of the above general character which may be inexpensively manufactured and assembled and applied to mines now of standard equipment without material alterations or modifications.

A further object is to provide a reliable 40 and efficient mechanism of compact construction for automatically calibrating a mine when launched either over the stern of the vessel or from a submarine tube.

While the invention will hereinafter be 45 described with relation to its application to mines it is, of course, to be understood that it is applicable to other types of floating bodies where it is desired to keep each body or member at a predetermined distance 50 below the surface of the fluid in which it is immersed.

Other objects will be in part obvious and in part hereinafter pointed out in connection with the accompanying sheets of drawings illustrating one of various possible embodiments and wherein similar reference characters denote corresponding parts. 60

In these drawings, Figure 1 is a longitudinal sectional view of a portion of the mine case with the invention applied thereto. 65

Figure 2 is a semi-diagrammatic view of the mine after being launched and,

Figure 3 is a similar view showing the mine in its final position.

Referring now to the drawing in detail 70 and more particularly, Figure 1, 10 indicates the mine case which is diagrammatically shown as spherical in shape although other shapes may be more desirable for use with mines adapted to be launched from 75 submarines.

The upper part of the mine case is usually provided with a buoyancy chamber and an opening is formed in the mine case to which the mechanism shown in Figure 1 is 80 attached. This mechanism includes a general cylindrical-shaped body 11 provided with an enlarged portion 12 forming a seat for a diaphragm 13 held in place by means of a coating member 14 provided with an opening 15 leading to the exterior of the mine.

A longitudinally disposed tubular member 16 is secured to the diaphragm as shown and provided with a valve 17 adapted to coat with a valve seat 18 mounted at 85 the end of a pipe or tube 19. This valve is normally held in restricted position by means of a spiral spring 20 whereby water is permitted to flow into a collapsible chamber 21 at the end of the pipe 19 after entering the openings 22 in the cap on the outer side of the mine casing. The water is free 90 to pass through the tubular member 16 and openings 23 until the pressure on the dia-

phragm 13 is sufficient to force the tube 16 to close the valve 17 against its seat 18 thereby to prevent a further amount of water entering the collapsible chamber 21. 95

By reference to Figures 2 and 3 it will be 100 seen that when the mine is thrown overboard it sinks until the float 24 is partially drawn under water. This float, however, is connected by means of a line 25 with the second float 26 as well as a line 27 leading to the mine. After the float 24 is submerged the spring 20 which is adjusted to 105 be compressed when the depth of the mine 110

exceeds the length of the line 27 thus permitting the closing of the valve 17 and preventing the consequent admission of any further ballast to the tank 21. The mine 5 continues to sink due to its slight negative buoyancy to the position shown in Figure 3 whereupon the float 26 constituting the necessary margin of safety overcomes this negative buoyancy and renders the entire unit 10 slightly buoyant thus keeping the mine at the desired predetermined depth below the surface.

It will thus be seen that the present invention contemplates a simple and practical apparatus well adapted to accomplish among others all of the objects and advantages herein set forth. In the embodiment 15 shown and described, two floats are used but such construction is not essential for the mine case itself may be made buoyant thereby to dispense with one of these floats. In such construction, however, the large amount of line is liable to become entangled thus somewhat reducing the reliability of 20 the construction in actual practice.

What I claim is:—

1. In combination with a member adapted to be suspended at a predetermined depth below the surface in which it is immersed, a ballast chamber, means for admitting fluid to said ballast chamber and hydrostatically controlled means for stopping the admission of fluid thereto after the member has reached a predetermined depth and means including a float adapted to prevent a further sinking of said member.

2. In combination with a member adapted to be suspended at a predetermined depth below the surface in which it is immersed, a ballast chamber, means for admitting the fluid to said ballast chamber, hydrostatically controlled means for stopping the admission of fluid thereto after the member has reached a predetermined depth, means adapted to prevent a further sinking of said member, said last mentioned means comprising two floats, one of which is adapted to retard the downward movement of the member and the second of which is adapted to render the entire unit slightly positively buoyant.

3. In combination with a mine adapted to be submerged at a predetermined depth, a ballast tank into which sea water is permitted to flow as the mine sinks, hydrostatically actuated means including a diaphragm, a valve and valve seat for closing

the admission to said ballast tank on the mine reaching a predetermined depth and a float flexibly connected with said mine 60 adapted to render the entire unit slightly buoyant after the valve is closed.

4. In combination with a mine adapted to be submerged at a predetermined depth, a ballast tank into which sea water is permitted to flow as the mine sinks, hydrostatically actuated means including a diaphragm, a valve and valve seat for closing the admission to said ballast tank on the mine reaching a predetermined depth, and 70 two floats connected one above the other with the mine case, one of which is adapted to retard the downward movement of the mine and the other adapted to render the entire unit slightly buoyant.

5. In combination with a mine case having a ballast chamber, an inlet to said ballast chamber including a diaphragm having a tubular member movable therewith under hydrostatic pressure, a valve associated with 80 said tubular member, a valve seat with which it coacts to close the entrance to the ballast chamber when the mine reaches a predetermined depth and means adapted to support said mine from the surface of the 85 water.

6. In combination with a mine case having a ballast chamber, an inlet to said ballast chamber including a diaphragm having a tubular member movable therewith under hydrostatic pressure, a valve associated with 90 said tubular member, a valve seat with which it coacts to close the entrance to the ballast chamber when the mine reaches a predetermined depth, said means including two floats, one above the other, one of 95 which is adapted to arrest the downward movement of the mine and the other of which is adapted to render the entire unit slightly buoyant.

7. In combination with a mine adapted to be submerged to a predetermined depth, said mine being provided with a ballast tank into which sea-water is permitted to flow as the mine sinks, hydrostatically actuated means adapted to close the admission of water to said tank when the mine reaches a predetermined depth and a float flexibly connected with the mine adapted to keep the mine suspended at its predetermined 105 depth.

Signed at New York, New York, this 16th day of April, 1924.

CLARENCE N. HICKMAN.
